UNITED STATES PATENT OFFICE.

CLYDE W. PRICKETT, OF WINTerset, IOWA,
CONCRETE AND WOOD FLOOR CONSTRUCTION DEVICE.

REISSUED

1,381,740.

Specification of Letters Patent. Patented June 14, 1931.

Application filed November 1, 1920. Serial No. 421,020.

To all whom it may concern:

Be it known that I, CLYDE W. PRICKETT, a citizen of the United States, and a resident of Winterset, in the county of Madison and 5 State of Iowa, have invented a certain new and useful Concrete and Wood Floor Construction Device, of which the following is a specification.

The object of my invention is to provide 10 a concrete and wood floor construction device of simple and inexpensive construction.

Considerable difficulty is involved in laying a wood floor on a concrete base, and it is my purpose to provide a construction, 15 whereby such a floor can be laid on a concrete base with the parts accurately placed in the proper position and at a minimum expense.

With these and other objects in view, my 20 invention consists in the construction, arrangement and combination of the various parts of my device, whereby the objects contemplated are attained, as hereinafter more fully set forth, pointed out in my claims, 25 and illustrated in the accompanying drawings, in which:

Figure 1 shows a detail, sectional, perspective view of a floor construction embodying my invention.

Fig. 2 shows a perspective view of the 30 means for fastening the sleepers to the concrete base; and

Fig. 3 shows a similar view illustrating the arrangement of the fastening devices 35 for shipping and storage.

Ordinarily in laying a wood floor on a concrete base, the concrete base is laid, then sleepers are placed in position on the floor and anchored from the ceiling, so as to hold 40 them in place. Nails or the like are driven in the sleepers, having preferably one beveled side edge, and an additional layer of thin concrete is poured between the sleepers for anchoring them.

This is a slow and expensive process, 45 which I have sought to avoid by means of my structure herein set forth.

In the accompanying drawings, I have used the reference numeral 10 to indicate 50 generally a concrete base. Properly spaced on the concrete base are sleepers 11.

For fastening the sleepers 11 to the base, I have provided the following means:

I provide a strip of metal, which is bent 55 to form a central, horizontal member 12, from which there extends downwardly arms

or portions 13, the lower parts of which are crimped, as illustrated at A. From the lower ends of the arms or portions 13, the strip is bent upwardly on each side, as at B, 60 and crimped, as shown for instance in Fig. 2.

The strip is long enough, so that the ends C extend upwardly substantially above the central portion 12. The ends C are provided with holes 14 to receive nails.

For storage or transportation, the ends C are bent over the member 12 and overlap each other, as illustrated in Fig. 3.

When the concrete base 10 is laid, and 70 while the concrete is still soft, the ends A and B are forced down into the concrete, as shown in Fig. 1, and the concrete is allowed to set. The bending over of the ends C as in Fig. 3, permits free use of the concrete 75 floor without interference by the fastening devices until such time as it is desired to lay the wood floors.

At the proper time the ends C are bent up to vertical position, as shown in Fig. 2, from 80 their positions shown in full lines in Fig. 3, and the sleepers 11 are laid between the spaced end members C, as shown in Fig. 1, and secured thereto by means of nails driven through the holes 14 into the sleepers.

By the use of the term "crimped" herein, I intend to include corrugations or any form of device having projecting elements for receiving proper anchoring in the concrete.

The sleepers will thus be accurately placed 90 and rigidly held in position with relation to the base 10. The flooring may be then nailed to the sleepers in the ordinary way.

By the construction herein shown, it will be seen that I am enabled to accurately and 95 rigidly place the sleepers in proper position with relation to the concrete base with a minimum of labor and expense.

I am able to avoid the anchoring of the sleepers, which is necessary under the old 100 process, which is expensive and involves the use of great care to prevent the slipping of the sleepers from their proper position, and I save the use of material necessary to provide a layer of concrete extending from the 105 base 10 part way up the sleepers 11.

I also greatly reduce the weight of the concrete base, thereby making it possible to use less material and lighter steel through the entire construction, where a building of 110 several stories is under construction.

It will be seen that my process involves

the pouring of a concrete base, the forcing therein while soft of the fastening device, having the member 12, which serves as a stop member, the allowing of the concrete to set, 5 the laying of the sleepers and fastening them to the fastening devices, and the laying of the floor on the sleepers.

Changes may be made in the details of the 10 construction of my floor structure and in the steps in the practice of my process, without departing from the spirit and purpose of my invention, and it is my intention to cover by my claims, any modified forms of structure or use of mechanical equivalents, or any 15 variations in the steps of the process, which may be included within their scope.

I claim as my invention:

1. A support for concrete and wood floor 20 construction, comprising a single piece of material bent to form a central member, downwardly extending parts at the ends thereof, the ends of the downwardly extending parts being re-bent upwardly and projecting upwardly above said central mem-

bers, and adapted to receive a steeper be- 25 tween them.

2. In a device of the class described, a fastener device comprising a single strip of material having a central member with bent down parts, crimped and re-bent upwardly 30 from the lower ends of the bent down parts, and projecting upwardly above said central member, and provided with openings for fastening said last-described parts to sleepers.

3. In a device of the class described, a fastener device comprising a single strip of material having a central member with bent down parts at the edges thereof, having their lower parts crimped and re-bent upwardly 35 from the lower ends of said downwardly extending parts crimped at their lower parts and projecting upwardly above said central member and provided with openings for fastening said last-described parts being made of material, which can be bent over said central member for reducing the bulk of said 40 device for transportation and storage.

CLYDE W. PRICKETT.
